UNITED STATES PATENT OFFICE.

DILLWYN M. BELL, OF DETROIT, MICHIGAN, ASSIGNEE TO JOHNSON FARE BOX COMPANY, OF CHICAGO, ILLINOIS, A CORPORATION OF NEW YORK.

FARE-BOX.

1,334,071.

Specification of Letters Patent. Patented Mar. 16, 1920.

Application filed April 18, 1916. Serial No. 91,900.

To all whom it may concern:

Be it known that I, DILLWYN M. BELL, a citizen of the United States, and a resident of the city of Detroit, in the county of Wayne and State of Michigan, have invented 5 certain new and useful Improvements in Fare-Boxes; and I do hereby declare that the following is a full, clear, and exact description of the same, reference being had to the accompanying drawings, and to the numerals of reference marked thereon, which form a part of this specification.

This invention relates to an improved type of fare box wherein the parts are compactly arranged for easy access and assembly, and removable as a unit from the inclosing casing by the simple detachment of a few bolts and screws.

It is an object therefore of this invention 20 to construct a fare register adapted to count and totalize the sum of a mixture of coins of different denominations, elevating the same one by one to a counting position whereby mechanisms are entrained according 25 to the diameter of the coin to effect a drive to the register whereby the same is actuated according to the denomination of the coin.

It is also an object of this invention to 30 construct a fare box adapted to receive an indiscriminate mixture of coins deposited therein to separate the same for movement one by one to counting position, whereby counting mechanisms are actuated according 35 to the denomination of the different coins and the sum total thereof indicated upon a register provided for the purpose.

It is also an object of this invention to 40 construct a fare register wherein the coins carried to a counting position operate according to their diameter to impart an initial movement to a coin lever which operates automatically thereafter to cause to be shifted into train mechanisms for actuating 45 a register upon which the sum of the various denominations of coins is totalized.

It is furthermore an important object of 50 this invention to construct a coin counting machine for coins of different denominations embodying an inclined carrying element for separating and elevating the various coins one by one to a counting position, whereby mechanisms are started in movement according to the diameter of the coins 55 to effect entrainment of driving means for

a register upon which the sum total of the various coins operated upon is registered.

It is finally an object of this invention to construct a simple and compact coin counting machine for coins of different denominations 60 providing a number of protective devices to prevent inaccurate registration of the coins either accidentally or through fraud.

The invention (in a preferred form) is 65 illustrated in the drawings and hereinafter more fully described.

In the drawings:

Figure 1 is a front face view of the slotted or recessed coin carrying disk or 70 wheel and auxiliary mechanisms associated therewith.

Fig. 2 is a rear elevational view thereof.

Fig. 3 is a reduced rear face view of the coin carrying wheel detached. 75

Fig. 4 is a section taken on line 4—4 of Fig. 2, with parts shown in elevation, and with a portion of the casing shown in section.

Fig. 16 is a development of the built-up mutilated gear.

Fig. 17 is a development of the retaining grooved cylindrical cam mounted on the 105 same shaft with said mutilated gear.

Fig. 18 is an exterior view of the fare box.

Fig. 19 is an elevation of the stationary inclined frame plate of the device. 110

Fig. 20 is a section on line 20—20 of Fig. 19.

As shown in the drawings:

In the exterior view of the fare box shown in Fig. 18, the main casing, which is substantially of rectangular shape, is denoted by the reference numeral 1, and has an upper smaller extension 2, on which is mounted a glass receiving compartment 3, provided with a mouth piece 4, at the upper end, through which the coins are admitted, the coins falling by gravity into and through a hopper 5, within said glass compartment. A drawer 6, is mounted in the lower end of the main casing 1, and is so positioned as to receive collected therein the counted coins discharged from the counting mechanisms mounted within the casing 1, hereinafter described. Mounted within the lower main casing 1, is a frame comprising a relatively heavy inclined plate 7, of substantially circular outline, and provided with an inwardly directed hub extension 8. Rigidly secured to said inclined plate 7, on the rear surface thereof is a pair of bracket plates 9 and 10, respectively, and secured therebetween to reinforce the same, are horizontal tubular rods 11 and 12, respectively. Attaching lugs 13, are formed on the lower end of the inclined plate 7, for attachment thereof to the wall of the casing 1. An inwardly directed attaching foot is formed upon the lower end of the respective bracket plates 9 and 10, denoted by the reference numerals 14 and 15, respectively, to afford an attachment upon a horizontal partition or wall 16, within the lower portion of the main casing 1, beneath which the drawer 6, is positioned. Journaled horizontally between the bracket plates 9 and 10, is a main drive shaft 17, with one end thereof projecting into a cylindrical casing 18, secured and attached in the bracket plate 10, within which is mounted a spring clutch of a well known and familiar construction by means of which a drive is imparted to the shaft 17, from a handle 19, attached on one member of the concealed clutch. Thus in the case of abnormal resistance to the movement of said shaft 17, the spring clutch will release and permit rotation of the handle 19, to take place without damage to the mechanisms of the fare box.

Journaled through the hub extension 8, of the inclined frame plate 7, is a shaft 20, and secured upon the inner end thereof is a relatively large bevel gear 21, meshing with and adapted to be driven by a small bevel pinion 22, secured upon said shaft 17. Secured upon the other end of said shaft 20, as clearly shown in Fig. 4, is a circular coin carrying wheel or disk 23, relatively thick at its center and thin along its outer margin and grooved out on the rear surface of said margin as denoted by the reference numeral

24, said grooved portion fitting over a circular raised rib 25, formed on the top surface of the inclined frame plate 7. The thickness of said coin wheel at the grooved out marginal portion thereof is less than half the thickness of a dime, being just thick enough to carry a coin along in a coin pocket. However, at the upper portion of the frame plate 7, the rib 25, tapers off flush with the surface of said plate on each side of the rib, the inclined or tapered off portion of said rib denoted by the reference numeral 25^a, and clearly shown in Fig. 19.

A plurality of coin pockets or recesses 26, are cut in the periphery of said coin carrying wheel 23, each pocket disposed over the rib 25, as clearly shown in Fig. 1, and intermediate said coin pockets a number of small rectangular apertures or slots 27, is provided, for a purpose hereinafter pointed out. Riveted to the rear surface of the coin carrying wheel 23, is a small circular disk 28, provided with arc shaped recesses 29, therein, as shown in Fig. 3, for a purpose hereinafter described. Bolted or secured in any suitable manner over the upper surface of the inclined frame plate 7, is a hopper 30, the upper open end of which registers beneath the extension 2, of the casing, to receive the coins from the glass compartment 3, therethrough into said hopper whereby the same are subsequently elevated to counting position in the coin pockets 26, of the carrying wheel. The coins swept upwardly by the coin carrying wheel 23, disposed in the pockets 26, thereof, are utilized as mechanical elements operating according to their diameter to actuate a coin lever at different intervals of time, to thereby cause the same to entrain a register with a driving means therefor to register the sum total of the different coins. Accordingly, a lever 31, is secured upon a short pintle shaft 32, extending rearwardly through the frame plate 7, at the upper end thereof, and secured over the outer surface of said lever 31, is a thin sheet of metal 33, which projects downwardly over the surface of the coins as the same are moved beneath the lever 31, to elevate the same.

Pivoted on an extension at the upper end of the inclined frame plate 7, is a presser plate of resilient metal 34, beneath which the coins are constrained to pass carried on the wheel 23, before passing beneath the coin lever 31, and a coiled spring 35, is mounted at the pivotal connection for said presser plate 34, to normally impel the same inwardly against the margin or periphery of the coin wheel 23. A confining plate 36, projecting over the upper portion of the coin wheel 23, is provided to prevent the coins falling from the wheel 23, as they pass beneath the coin lever 31, and has a sharpened stripper projecting 36^a, and a lever 37, is pivoted on the outer surface of

said plate 36, and is provided with a spring impelled finger 38, beneath which the coins which have actuated the lever 31, are constrained to pass and are struck thereby from the pockets 26, of the coin wheel through an aperture provided in the frame plate 7, to fall downwardly through a discharge chute 39, into the collection drawer 6. A leaf spring 40, is also mounted on the outer surface of said plate 36, and bears upon said lever 37, to impel the same inwardly, so that the finger is always held resiliently against the coins passing therebeneath.

Mounted in a yoke shaped frame 41, which is secured upon the rear surface of the frame plate 7, is a series of associated register wheels or dials 42, each having a pinion 43, and mutilated gears or one toothed disk 44, connected therewith for operation in a familiar and well known manner, by which, through the intermediation of groups of associated pinions 45, and star wheels 46, journaled on a shaft parallel to the shaft on which said register dials are mounted in the frame 41, movement is transmitted from one register dial to the next adjacent. That is to say, with one revolution of the units dial, the next dial or tens dial receives a movement of one division, and with one revolution of the tens dial the hundreds dial adjacent thereto receives imparted thereto a movement of one division. Movement is transmitted directly to the units dial through the gear 43, thereof, by a pinion 45, which receives its movement from an idler pinion 47, meshing with a pinion 48, feathered upon a slideable shaft 49, which is journaled horizontally at the rear of the frame plate 7.

Mounted on one end of the main driving shaft 17, is a built-up or composite mutilated gear consisting of five disks 50, 51, 52, 53, and 54, respectively, of which the last four are gear sections and have teeth thereon to drive a pinion 55, secured upon the slideable shaft 49, and capable of being moved therewith into a position to engage one of the groups of teeth of said built-up composite gear. The shaft 49, is caused to slide to move the pinion 55, into mesh with the mutilated composite gear by movement initiated by the coin lever 31, when a coin passes therebeneath.

For this purpose, connected on the end of the pintle 32, for said coin lever 31, is a long lever 56, having a short cylindrical extension 57, on the rear surface thereof, which engages in a collar 58, which is mounted on the shaft 49, so that movement of the lever 56, is transmitted to said shaft 49, to slide the same. The initial movement of the lever 56, is continued independent of the coin by a spring latching means or detent, which normally retains said lever retracted against accidental movement by vibration

or otherwise, comprising a pivoted notched plate 59, mounted on a pintle 60, secured in a bracket attached to the bracket plate 10, and normally impelled into engagement with a pin 61, on said lever 56, by a spring 62. The initial movement of the lever 56, is imparted thereto by the coins through the coin lever 31, the movement taking place sufficiently to cause the pin 61, to ride out of the notch in the plate 59. The inclined or pointed end of said plate 59, then engages behind the pin 61, to continue the movement of the lever 56, thereaway from under the stress of the spring 62. Secured perpendicularly on the rear surface at the lower end of the lever 56, is a tooth 63, and secured upon the main shaft 17, is a multiple grooved cam 64, one groove for each denomination of coin to be counted corresponding with the respective rows of teeth on the composite mutilated gear, also on said shaft 17.

As shown in the development view of said cam element 64, in Fig. 17, the entrance for each of the grooves therein leads inwardly at an angle from one edge of the cam at different points on the periphery, so the time at which the coin lever 31, is actuated by a coin, determines with which of the grooves the tooth 63, on the lever 56, is projected into engagement. As the tooth 63, rides inwardly along the inclined wall at the entrance of each of the grooves, it necessarily moves said lever 56, inwardly an amount sufficient to bring the tooth into the plane of the groove on the periphery of the cam, thereby sliding the pinion 55, with said shaft 49, an amount to insure engagement of said pinion 55, with the proper group of teeth on the composite mutilated gear to transfer a movement through said shaft 49, to the register, to effect proper registration of a coin which first initiated the movement of the coin lever 31. After the movement has been transmitted to the pinion 55, by one of the groups of teeth on the mutilated gear, the tooth 63, strikes against the inclined abutment wall 65, at the ends of the respective grooves on the cam element, causing the tooth to ride outwardly, thereby swinging said lever 56, outwardly into initial position, whereby the pin 61, thereon, engages over the pivoted detent plate 59, and of course withdrawing the pinion 55, into a position at rest over the disk element 50, of the mutilated gear, which serves to prevent accidental rotation of the pinion 55, or shaft 49, therewith.

As clearly shown in the development view in Fig. 16, the disk element 54, of the mutilated gear is provided with four teeth to rotate the pinion 55, an amount sufficient to register five counts on the register: the element 52, is provided with nine teeth to rotate the pinion 65, an amount sufficient to actuate the register to count ten units, and the

element 51, is provided with four teeth to actuate the pinion 55, sufficient to count five units on the register. The construction of the disk 53, whereby the pinion 55, is only 5 rotated one tooth to count a penny on the register, is peculiar, in that a pivoted toothed element 66, is provided, mounted in a recess in said disk 53, as shown in Fig. 15, normally impelled outwardly by a spring 67, so 10 that as the forward end of said lever 66, strikes the tooth on the pinion 55, the next succeeding tooth on said pinion 55, strikes downwardly on the surface of said lever 66, to thrust the same inwardly, thus riding 15 thereover and receiving no further movement therefrom.

Means are provided to strike off from the carrying wheel 23, any coins which might, by accident, be improperly carried upwardly 20 thereby, either improperly seated in the coin pockets 26, or adhering to the coin wheel at points between the pockets. Said means are constructed to project through slots in the frame plate 7, and through the slots passing 25 thereover provided in the coin wheel 23, to strike off the improperly carried coins. Accordingly, secured upon the rear surface of the frame plate 7, is a bracket plate 68, on which is pivoted two integrally connected 30 arms 69, which are joined at their outer ends by a cross piece 70, and a coiled spring 71, is coiled about the pivotal connection of said arms 69, on said bracket plate 68, to normally thrust the outer pointed ends of 35 said arms 69, through slots provided in said plate 7, one of which is denoted by the reference numeral 72, and the other of which is concealed beneath the carrier wheel 23, and when the slots 27, on said carrier wheel 40 register therewith, the pointed ends of said arms project therethrough under the impulse of the spring therefor. As a result of the constant succession or passage of the slots 27, in the carrying wheel over the slots 45 in the frame plate 7, the pointed ends of said striker arms 69 are oscillated for successive projections through said slots. Another pair of integrally connected striker arms, denoted by the reference numeral 73, 50 are pivotally mounted upon the rear of the frame plate 7, in a bracket 74, and are actuated inwardly by a coiled spring 75, whereby the pointed end of one of the striker arms 73, is adapted to project through a slot 76, 55 provided in the frame plate 7, and the other is adapted to project through a similar slot beneath the carrying wheel 23, and through one of the slots 27, as the same registers therewith, so that a constant successive projection of the pointed ends of said striker arms is made as the carrier wheel 23, is rotated. The respective slots 72 and 76, visible 60 in Fig. 1, are shown disposed beyond the periphery of the carrier wheel 23, and the 65 striker arms project therethrough only at

the time the slots 27, of said carrier wheel, are in register with the corresponding slots in the frame plate 7, therebeneath, and due to the fact that said slots 27, are disposed between the pockets 26, the striker arms do 70 not project through the plate 7, when a coin pocket 26, is passing by, thus allowing a coin seated therein to move on to counting position. Means are also projected through slots in the frame plate 7, beneath the resilient presser plate 34, beyond the periphery of the carrier wheel 23, to strike off coins if by chance any coin should be conveyed to this point, otherwise than properly seated in the carrier pocket 26, as, for instance, 75 when two coins are stuck together and one properly seats in the coin pocket 26, and the other is carried therewith upwardly beneath the presser plate 34. For this purpose, pivoted in extensions 77, formed on a bracket 80 disposed beneath the lower end of the yoke frame 41, which supports the register dials, is a long lever or arm 78, shown in detail in Fig. 6. The lower end of said lever 78, is bent inwardly at right angles and provided 85 with a pointed end or tooth 79, which, due to the action of gravity on the longer arm of the lever, is thrust inwardly against the rear surface of the disk 28, on the carrier wheel, whereby the head 79, seats in the 90 slots 29. The upper end of said lever 78, is provided with two long curved fingers 80 and 81, substantially at right angles to the lever 78, and when the inwardly held head 79, on the lower end of said lever 78, is 95 forced outwardly by the partition walls between the slots 29, said fingers 80 and 81, are projected through a long slot in the frame plate 7, and beyond the same close to the periphery of the carrier wheel 23. The 100 finger 81, as shown in Fig. 7, strikes beneath the presser plate 34, near the pivoted end thereof, to swing the same outwardly as said fingers 80 and 81, are projected through the slot in the frame plate, so that in the 105 event that the fingers 80 and 81, strike a coin improperly positioned, the presser plate is 110 swung outwardly to permit the coin to fall downwardly over the surface of the carrier wheel.

The operation is as follows: 115
The coins or fares are deposited through the mouth 4, of the fare box, falling through the hopper 5, into the inspection part 3, and are then dumped by the operator, by means 120 not shown, through the extension 2, of the casing, falling therethrough into the coin hopper 30, within the main casing 1, shown in Fig. 4. The operator then operates the handle 19, which is exposed on the exterior 125 of the casing on the side opposite from that shown in Fig. 18, to drive the mechanisms of the fare register, whereby the rotation of the coin carrier wheel 23, causes the coins of different denominations to be picked up in 130

the coin pockets 26, and swept over the stationary plate 7, upwardly toward counting position. The machine is adapted to handle coins of different denominations, to-wit, 5 Canadian five cent pieces, dimes, pennies and nickels, and the pockets 26, are adapted to carry only one coin, and in the event that more than one coin should be carried therein or on any other portion of the disk, the 10 striker elements projected through the slots 27, and slots 76 and 72, on the frame plate 7, will serve to strike the same from the carrying wheel. In the event that two coins adhere to one another, the stripper point 36^a, 15 disposed over the carrier wheel at the upper end thereof, as shown in Fig. 1, will serve to strip the outer coin from the one beneath, and the striker means 80 and 81, will be projected through a slot in the frame plate 7, 20 to strike the stripped coin from beneath the presser plate 34, which swings outwardly on its pivotal connection under the impulse of the striker arm 81, to permit the coin to fall downwardly into the hopper to 25 be picked up at a subsequent time.

As the coins are picked up and carried in the coin pockets 26, they slide along on the rib 25, of the stationary plate 7, swept thereover by the coin wheel, and as the coin 30 approaches counting position it slides deeper into the coin pocket 26, due to the tapering away of the portion 25^a, of the rib 25. As a result, the rear or driving edge of the coin pocket has a larger bearing surface on the 35 rear edge of the coin to thrust the same along for utilization as a mechanical element. It has been actually demonstrated that the tapering off of the rib 25, to provide a deeper carrying pocket for the coin has 40 permitted use of the machine at extremely high speeds, in fact doubling the counting capacity thereof as compared with a machine in which the rib 25, is not tapered away.

45 Due to the fact that the different denominations of coins adapted to be handled by the machine are of different size and of different diameters, the coin lever 31, the end of which bears downwardly upon the 50 peripheral edge of the carrier wheel 23, is necessarily elevated at different intervals of time with respect to a coin pocket passing therebeneath for different coins carried, that is to say, a nickel, due to its large diameter, 55 will cause an elevation of the coin lever 31, before a penny similarly carried, and likewise a penny will effect an elevation of said coin lever 31, before a dime, and a dime will elevate the coin lever 31, before a Canadian 60 five cent piece carried in the pocket on the wheel. These differences in time of elevation of the coin lever 31, with reference to a coin pocket on the carrier wheel are utilized in effecting a shift of a selective mechanism 65 to register the coins which first elevate the

coin lever 31. It is only an initial movement of the coin lever 31, which is imparted thereto by the coin of course passing therebeneath, causing a similar movement of the lever 56, connected to the same pivot shaft 70 32. After the initial movement has been transferred to the lever 56, by the coin, the movement is continued by the pin 61, on the rear surface of said lever, shown in Fig. 5, 75 riding out of the notch of the spring impelled detent plate 59, impelling the plate downwardly, whereupon the inclined edge of said plate contacts behind the pin 61, to throw said lever 56, still farther to one side, whereupon the pin 63, moves into one of the 80 entrance passages to the grooves on the multiple grooved cam element 64. Inasmuch as the coin only institutes a movement which is continued by positive mechanical means, it is 85 obvious that the wearing effect on the coin is very slight and mutilation of the coins by the machine is avoided. The entire movement of the lever 56, has been transmitted to the slidable shaft 49, through the rounded pin 57, on said lever 56, engaging the collar 90 58, on said shaft, thus shifting the pinion 55, mounted rigidly on said shaft into a selective position for engagement with one series of teeth on the composite mutilated gear, so that the continued rotation of the handle 19, 95 by the operator causes said mutilated gear to drive the pinion 55, and thereby drive the register the proper amount to register the coin which first initiated the movement of the coin lever 31. After registration of the 100 coin, the tooth 63, on said lever 56, by the continued operation of the cam 64, by the handle 19, strikes against the inclined abutment 65, on the cam element, and is forced out of engagement with said cam, causing 105 the lever 56, to be retracted to initial position the pin 61, sliding over the inclined end of the plate 59, which is sprung to permit the pin to engage in the detent plate 59, 110 to thus prevent accidental movement thereof such as by tilting the machine, and the pinion 55, is moved to neutral over the disk 50, of the composite mutilated gear, said disk serving to prevent rotation of the pinion 55, and thus, accidental movement of the 115 register dials. The coin on the carrier element is carried on beneath the plate 36, so that it passes beneath the spring impelled finger 38, which projects through a slot in said plate and serves to thrust the coin from 120 its pocket in the carrier wheel into an aperture, shown in dotted lines in Fig. 5, provided in the frame plate 7, as the pocket passes thereover, the coin then falling through the chute 39, at the rear of the 125 frame plate downwardly in the casing and into the collection drawer 6.

I am aware that various details of construction may be varied through a wide range without departing from the principles 13

of this invention, and I therefore do not purpose limiting the patent granted otherwise than necessitated by the prior art.

I claim as my invention:

5. 1. In a fare register of the class described, a coin carrier wheel for coins of different denominations, a coin lever positioned to contact the coins carried by the coin wheel, a lever connected to said coin lever to receive its initial movement therefrom due to contact with a coin, a spring detent from which said second mentioned lever is released by such movement which acts to continue the movement of said second mentioned lever after release thereof therefrom, means to engage with said second mentioned lever to continue the movement thereof to a selective position, a register, and mechanism shifted by said second mentioned lever to 20 driven position to drive said register.

2. In a device of the class described, a coin carrier wheel having pockets therein, a lever adapted to be elevated at different times by coins carried on said wheel according to the denominations of the coins, a register, a drive therefor, means movable into a selective position with reference to said drive for transmitting the drive to said register according to the denomination of the 30 coins, a lever connected to said coin lever for shifting said means, a spring detent for holding said second mentioned lever in retracted initial position and acting when moved out of engagement therewith to urge the same outwardly, and means for engagement with said second mentioned lever to continue the movement thereof and to move the same into such position of movement until registration of the coin has been effected.

3. In a machine of the class described, a register, means carrying coins, mechanisms disposed for actuation by the coins on said means, a selective gearing to drive said register operated to proper selective position according to the denomination of the coins by said mechanisms, a pin connected with said mechanisms and a spring detent plate normally engaging said pin for holding said mechanisms in initial position and acting by release thereof from said detent plate to again engage said pin to urge the mechanisms outwardly toward selective position.

4. In a device of the class described, a rotatable coin carrying wheel, a coin lever disposed adjacent thereto pivoted for movement by coins carried on said wheel, a register to register the coins, a selective driving mechanism for said register, mechanism connected to said coin lever to shift said selective driving mechanism to actuate the register in accordance with the denomination of coin moving said coin lever, and a spring controlled plate to resist initial movement of the coin lever and thereafter urge the

same outwardly in its movement to shift said selective mechanism.

5. In a machine of the class described, a rotatable coin carrying wheel, a coin lever disposed adjacent thereto for actuation by a coin as a mechanical element carried on said wheel, a register to register the sum total of the coins collected, a selective driving mechanism for said register, means connected to said coin lever to operate said selective mechanism into proper position to actuate the register, and a spring detent plate engaging said means in normal position to resist movement thereof and after initial movement thereof urging the same 80 onwardly to accentuate the movement imparted thereto through said coin and coin lever.

6. In a coin counting machine of the class described, a rotatable coin carrier having pockets therein for coins of different denominations, a coin lever disposed for contact with said coins to be elevated at different times with respect to said coin carrier according to the different denominations of 90 coins carried, a register, a selective driving mechanism therefor, means connected to said coin lever to shift the selective driving mechanism for the register into driving train with said register, and a spring impelled plate co-acting with said mechanism to maintain the same normally in initial position and acting to urge the same outwardly in a shifting movement after initial movement imparted thereto by the coin as a mechanical element.

7. In a coin counting machine of the class described, an inclined frame plate, a rotatable coin carrier mounted thereon, a driving shaft journaled horizontally behind said frame plate, a shaft journaled axially through and perpendicular to said frame plate and connected to said coin carrier, a bevel gear secured upon said shaft, a bevel pinion secured upon said main driving shaft meshing with said bevel gear to drive said coin carrier from said main shaft, a multiple grooved cam mounted on said main shaft, a composite multilated gear mounted on said main shaft, a register, a 105 sliding shaft, a pinion thereon adapted when said shaft is moved to engage one of the series of teeth on said composite multilated gear, and means adapted for contact by a coin carried on said carrier element to 110 shift said shaft, said means adapted to be held in a shifted position by said multiple grooved cam.

8. In a machine of the class described, an inclined frame plate, a coin carrying wheel mounted thereon adapted to sweep coins thereover, mechanism adapted for contact by the carried coins to be moved according to the denomination of the coin, a main drive shaft, a composite multilated gear 125

having a plurality of series of teeth there-around mounted on said shaft, a multiple grooved cam also mounted on said shaft, a register, sliding means adapted to effect 5 driving engagement between said composite mutilated gear and said register to actuate the register in accordance with the denomination of the coin, and means connected to said coin lever adapted to co-act with said 10 multiple grooved cam to effect a final shifting movement of the drive for said register and hold the same entrained until registration of the coin has been effected.

9. In a machine of the class described, a 15 stationary element, a coin carrying wheel thereon, inclined means on said stationary element against which the coin is carried by said wheel to increase the degree of engagement of the coin with said wheel as the coin is moved into counting position, a coin lever on said stationary element adjacent said wheel and pivoted for movement by said coin, a register for registering the coin, a selective driving mechanism for said 20 register, lever mechanism connected to said coin lever to simultaneously shift said selective driving mechanism to actuate the register as said coin lever is moved into position to actuate said coin lever in accordance with the denomination of said 25 coin, and a spring controlled means on said stationary element to resist initial movement of the coin lever and lever mechanism and thereafter urge the same onwardly in its movement to shift said selective mechanism.

10. In a device of the class described, a coin transferring means for moving coins to a counting position, a register, a double lever mechanism adapted to be set in operation by coins carried by said coin transferring means to operate said register, spring controlled means for normally holding said double lever mechanism in initial position 45 and then acting to urge said double lever mechanism onwardly toward a selective position, and pivotally mounted finger means adapted to strike off coins improperly carried by said coin transferring means.

50 11. In a device of the class described, a drive shaft, a slotted cam thereon, a differential gear thereon, a coin carrying element rotated from the drive shaft, a lever operated by coins carried thereby, a second lever movable with said lever, a tooth thereon adapted to engage in one of the grooves in the cam, a counting wheel connected to be shifted by the second named lever into engagement with the differential gear and a 55 registering mechanism operated by the counting wheel.

12. In a device of the class described, a drive shaft, a slotted cam thereon, a differential gear thereon, a coin carrying element, 60 rotated from the drive shaft, a lever oper-

ated by coins carried thereby, a second lever movable with said lever, a tooth thereon adapted to engage in one of the grooves in the cam, a counting wheel connected to be shifted by the second named lever into engagement with the differential gear, a registering mechanism operated by the counting wheel and a mechanism for engaging the second named lever for holding the same from accidentally shifting the counting 70 wheel into engagement with the differential gear. 75

13. In a device of the class described, a coin carrying wheel, a register, a cam member, a differential gear rigidly connected to 80 rotate with the cam, a counting wheel adapted to mesh with any of the sets of teeth on the differential gear, a lever connected with the counting wheel to shift the same, means contacted by the coin for starting movement 85 of the lever, means for preventing accidental movement of the lever and adapted when the lever is started in motion to continue the motion of the lever, and means on the lever engaging the cam to complete the motion 90 of the lever in adjusting the counting wheel into operative position.

14. In a device of the class described, a coin carrying wheel, a register, a cam member, a differential gear rigidly connected to 95 rotate with the cam, a counting wheel adapted to mesh with any of the sets of teeth on the differential gear, a lever connected with the counting wheel to shift the same, means contacted by the coin for starting movement 100 of the lever, means for preventing accidental movement of the lever and adapted when the lever is started in motion to continue the motion of the lever, means on the lever engaging the cam to complete the motion of 105 the lever in adjusting the counting wheel into operative position, and means for positively retracting the lever to be engaged by said means for preventing accidental movement of the lever. 110

15. In a device of the class described a register, mechanism for actuating the same normally having one part disengaged from the other, means for effecting the engagement of the mechanism, mechanism for releasably holding said means against accidental movement adapted after initial movement to continue the movement of the means, mechanism for completing the movement of said means, and mechanism moved by 115 the coins counted for effecting the initial movement of the said means. 120

16. In a device of the class described, a register, a coin carrying element, a member contacted by the coins as swept therewith, a lever moved by said member, a mechanism holding said lever from accidental movement and upon positive movement of the lever adapted to release the lever and to continue the throw thereof, mechanism for posi- 125 130

tively continuing the throw of the lever, and mechanism entrained by the throw of the lever to operate the register.

17. In a device of the class described, a register, a coin carrying element, a member contacted by the coins as swept therepast, a lever moved by said member, a mechanism holding said lever from accidental movement and upon positive movement of the lever adapted to release the lever and to 10 continue the throw thereof, mechanism for positively continuing the throw of the lever,

mechanism entrained by the throw of the lever to operate the register, and means for positively returning the lever to the holding mechanism preparatory to another count. 15

In testimony whereof I have hereunto subscribed my name in the presence of two subscribing witnesses.

DILLWYN M. BELL.
